(57) **CLAIM**

The ornamental design for a drink pouring dispenser, as shown and described.

DESCRIPTION

FIG. 1 is a first side view of a drink pouring dispenser, showing our new design;

FIG. 2 is a second side view of the drink pouring dispenser;

FIG. 3 is a third side view of the drink pouring dispenser;

FIG. 4 is a top view of the drink pouring dispenser; and,

FIG. 5 is a bottom view of the drink pouring dispenser.

The portions of the drink dispenser which are shown in broken lines form no part of claim. The dot-dot-dash line on FIGS. 3 and 4 disclose the boundary of the claim.
